ABSTRACT: A railway coupler shank mounting comprises a pin extending through a pinhole of the shank and seated against a complementary cylindrical surface of a pin-bearing block which is seated against a complementary spherical surface of the shank defining the rear extremity of the pinhole. The block is recessed at the top and bottom of said spherical surface to prevent stress concentration on the shank at the upper and lower rear corners of the pinhole during extreme vertical angling of the coupler shank. Also the contour of the pinhole and block have been changed to minimize downward movement of the block from its normal and proper position during buffing forces on the coupler. Top and bottom edges (41 of FIG. 10) are made on a full radius (42) to reduce stress concentration in the rear corner areas under normal draft use and/or during angling up or down.

BEARING BLOCK CONTOUR

This invention relates to a railway coupler shank mounting wherein a coupler shank comprises a pinhole receiving a pivot pin bearing block in spherical face engagement with the shank and in cylindrical face engagement with the pin to accommodate vertical and horizontal angling of the shank.

A primary object of the invention is to recess the top and bottom of the block along its spherical coupler-shank-engaging surface to prevent stress concentrations at the lower and upper rear corners of the coupler shank pinhole during upward and downward angling of the shank, respectively.

Another object of the invention is to minimize downward shifting of the block from its normal position when the coupler shank is urged against the pin under buffing forces.

The foregoing and other objects and advantages of the invention will become apparent from the following specification and the accompanying drawings, wherein:

FIG. 1 is a central vertical sectional view through a railway coupler shank mounting embodying the invention;

FIG. 2 is a view corresponding to FIG. 1 but showing the coupler shank angled upwardly;

FIG. 3 is a view corresponding to FIG. 1 but showing the coupler shank angled downwardly;

FIG. 4 is a view corresponding to FIG. 1 but showing the novel pin-bearing block thereof in assembly with a prior art coupler shank;

FIG. 5 is a view corresponding to FIG. 4 but showing the prior art coupler shank angled upwardly;

FIG. 6 is a view corresponding to FIG. 4 but showing the prior art coupler shank angled downwardly;

FIG. 7 is a side elevational view of the novel pin-bearing block;

FIG. 8 is a top plan view of the block;

FIG. 9 is a side elevational view of the novel coupler shank shown in FIG. 1; and

FIG. 10 is a top plan view partly in section along the horizontal median plane of the novel coupler shank as indicated by line 10—10 of FIG. 9.

Describing the invention in detail and referring first to FIG. 1, the novel coupler shank 12 comprises a pinhole 14 for reception of a substantially cylindrical pivot pin 16 also received in complementary pinholes 18 of a conventional yoke 20.

The top of the yoke is engageable with a conventional yoke guide wearplate 22, and the bottom of the pin 16 rests on a conventional yoke support plate 24, the plates 22 and 24 being attached to a car body in well-known manner.

A novel block 26 comprises a spherical face 27 seated against a complementary surface 28 of the coupler shank 12 defining the rear extremity of its pinhole 14. The block 26 engages the pin along a complementary cylindrical surface or area 29 of the block to accommodate horizontal angling of the coupler, and the surface 27 of the block is recessed as at 30, 30 so that upon upward angling of the coupler shank (FIG. 2) stresses are not concentrated at the shank surface 28 at the lower corner of said surface 28 defining the lower rear edge of pinhole 14, and similarly upon downward angling of the coupler shank (FIG. 3) stresses are not imparted to the upper corner of surface 28 defining the upper rear edge of pinhole 14.

Referring now to FIGS. 7 and 8, the novel pin-bearing block 26 is shown in detail and the prior art contour of surface 27 is shown by phantom lines at 32, 32 in FIG. 7. Another feature of the novel block is that the top and bottom lips or collars 34 and 36 thereof are spaced from the lateral sides or edges 37 of the block 26 and are formed on a 1 15/16-inch radius indicated at 39 (FIG. 8) to accommodate tilting thereof relative to the coupler shank in its pinhole 14 as shown in FIGS. 2 and 3. The prior art contour of these lips or collars 34 and 36 are shown in phantom lines at 39a matching the contour of prior art shank surfaces 46 (FIG. 10).

Opposite sides 37 of the block 26 are provided with spring holes 38, each hole being adapted to receive a coil spring (not

shown) compressed against a recessed surface 40 (FIGS. 9 and 10) in the coupler shank 12 at one side of its pinhole 14.

FIG. 10 also shows that surfaces 41 are formed on a 1 15/16-inch radius 42 struck from a point 44 on the vertical median plane y—y of the shank 12 rearwardly of the vertical median plane X—X of the pinhole 14. The prior art contour of each surface 41 is shown at 46 formed on a radius 48 struck from point 50 on plane Y—Y forwardly of plane X—X. Surfaces 41 better distribute stresses instead of concentrating stress in relatively sharp corners 46 of prior art.

Referring now to FIGS. 9 and 10 it will be seen that the surface 52 defining the forward extremity of pinhole 14 is V-shaped in vertical cross section with the apex of the V being formed on a 1 15/16-inch radius 54 (FIG. 10) struck from a point 56 at the intersection of plane X—X, plane Y—Y, and plane 10—10 shown in FIG. 9. The prior art contour of surface 52 is shown in phantom lines at 58 in FIG. 9.

Thus it will be understood that the novel pinhole 14 greatly reduces any tendency of the block to slide downwardly from its normal position shown in FIGS. 1-3, particularly under buffing conditions (not shown) wherein the apex of surface 52 engages the pin 16. It will also be understood that in prior art arrangements wherein the block did move downwardly from normal position very undesirable high stresses were imparted to the block and shank.

The butt end of the shank 12 comprises a spherical surface 60 adapted to seal against a complementary front draft gear follower (not shown) carried within the yoke 20 in the usual manner.

FIGS. 1-3 show the novel block 26 assembled within a pinhole 14 of a novel coupler shank shown in FIGS. 9 and 10. FIGS. 2 and 3 show respectively the extreme upward angled position and the extreme downward angled position of the coupler shank 12. FIG. 2 shows that lower recess 30 prevents stress concentration at the lower rear corner of pinhole 14 under these conditions, and FIG. 3 shows that upper recess 30 prevents stress concentrations at the upper rear edge of the pinhole under the conditions of FIG. 3.

Referring now to FIGS. 4-6 the novel block 26 is shown assembled in a pinhole 14 of a prior art coupler shank 12 having the prior art bearing surfaces 46 and 58.

FIGS. 5 and 6 show respectively the extreme upward angled position and the extreme downward angled position of the coupler shank 12. FIG. 5 illustrates that lower recess 30 prevents stress concentration at the lower rear corner of pinhole 14 under those conditions even though the block surface 27 has partially lifted off the shank surface 28. Similarly referring to FIG. 6 it will be seen that in the extreme downward angled position of the coupler shank 12, the upper recess 30 eliminates stress concentration at the upper rear edge of pinhole 14 even though block surface 27 has lifted off the lower portion of surface 28.

What is claimed is:

1. A railway coupler shank having a pinhole partly defined by a substantially spherical pin-bearing-block-engaging surface, the top and bottom of said surface being bounded by spaced substantially cylindrical top and bottom pin-bearing block-engaging surfaces, each of said top and bottom surfaces being formed on a radius struck from a point rearwardly of the transverse vertical centerplane of said pinhole to equalize and distribute stress.

2. A railway coupler shank according to claim 1 wherein said radius is approximately 1 15/16 of an inch in length to reduce or eliminate stress concentration.

3. A railway coupler shank according to claim 1 wherein the front of said pinhole is defined by a cylindrical surface which is V-shaped in vertical cross section, the apex of said V being formed on a radius struck from said centerplane, said radius being approximately 1 15/16-inches in length.

4. A railway coupler shank having a pinhole partly defined by a cylindrical front surface which is V-shaped as seen in vertical sectional view and has the apex of said V at substantially the horizontal median plane of the shank, said apex being

formed on a substantially 1 15/16 -inch radius struck substantially from a point on the transverse vertical median plane of said hole at its intersection with the horizontal median plane of the shank, a rear surface which is substantially spherical defining the rear extremity of the hole and top and bottom

abutments above and below said rear surface and each formed in horizontal curvature on a substantially 1 15/16-inch radius struck from a point on substantially the longitudinal vertical median plane of the shank rearwardly of said transverse plane.
